[57] CLAIM

The ornamental design for a container for candy or the like, substantially as shown and described.

DESCRIPTION

FIG. 1 is a perspective view of a container for candy or the like showing our new design;

FIG. 2 is a side elevational view thereof;

FIG. 3 is a rear elevational view thereof;

FIG. 4 is a front elevational view thereof;

FIG. 5 is a top plan view thereof; and

FIG. 6 is a bottom plan view thereof.

The design is characterized by a top wall having a circular shallow flat depression therein which has an etched surface texture which is in contrast to the flat surface texture of the remainder of the container and a front wall having a generally trapezoidal shallow flat depression therein adjacent the top wall.
